UNITED STATES PATENT OFFICE.

JOHN WICKS, OF OAK PARK, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Application filed January 19, 1920, Serial No. 352,420. Renewed January 26, 1925.

To all whom it may concern:

Be it known that I, JOHN WICKS, a citizen of the United States of America, and resident of Oak Park, Cook County, Illinois, ⁵ have invented certain new and useful Improvements in Measured-Service Telephone Systems, of which the following is a specification.

My invention relates in general to measured service telephone systems and more particularly to automatic measured service systems of the type in which paystation apparatus is provided at each subscriber's station requiring the deposit of a coin to pay ¹⁰ for each successful connection. In a proposed arrangement, and one which has been used to some extent, the calling device at the subscriber's station is normally inoperative to control the central office switches, and ¹⁵ it is only by first depositing a coin in the paystation apparatus that the subscriber is enabled to clear his calling device for use in operating the central office switches to set up a connection with a called line. Thereafter ²⁰ the deposited coin is either collected or refunded depending on whether the called subscriber does or does not answer his telephone and is refunded in any case if the called party is an operator or official at the ²⁵ telephone office.

In such a system, the calling device is inoperative for any purpose until a coin is deposited. The system is open to the objection that a coin of proper denomination ³⁰ is absolutely required before any connection can be established, even to an operator, and if the subscriber does not happen to have the proper coin at hand, he is entirely without recourse. Great damage might be done ³⁵ where in an emergency it is necessary to call the fire or police dept. and such connection is prevented because of the lack of an insignificant coin.

In order to overcome this difficulty, I have ⁴⁰ devised a measured service system operating along the same general lines as the system described, but in which only a certain plurality of the switches require the deposit of a coin before they can be operated, and in ⁴⁵ which one or more switches of this type are necessarily included in every connection which is extended to another subscriber's line. Other switches having a slightly different circuit are provided which are op-

erable without depositing a coin, and the ⁵⁵ trunking arrangement is such that a connection to an operator may be established exclusively through these latter switches. Thus in my improved system a calling subscriber may obtain connection with an operator at any time without depositing a coin, while if the connection is to be extended to another subscriber's line a coin must be deposited; and it may be stated that the provision of a system having these characteristics ⁶⁰ is the principal object of the invention.

Other objects have to do with the provision of a repeater circuit having an improved circuit arrangement for collecting ⁷⁰ and refunding deposited coins, and providing an improved talking circuit between connected lines, all of which, together with the principal feature of the invention, will be described in detail hereinafter, reference ⁷⁵ being had to the accompanying drawings.

Referring to the drawings, comprising Figures 1 and 2, the general layout of the system shown therein may be described briefly as follows: The substation A in Fig. ⁸⁰ 1 is an automatic telephone substation of the usual type and comprises the ordinary talking apparatus and an automatic calling device or impulse sender. Being a measured service substation there is also provided a well known type of coin collecting mechanism, which may be of the type shown and described in the United States Patent to Forsberg, No. 1,043,219.

The line conductors 21 and 22 extend to the exchange where they terminate in the individual line switch or trunk selector C, which is of the well known rotary type in which the wipers always remain on the contacts last used, and whose function it is to extend the line when calling to a trunk line which terminates in an idle first selector switch. One of the trunk lines to which the line switch C has access is shown extending to the first selector E, Fig. 2. The relay equipment in Fig. 1, which is indicated by reference character D, is a repeater, there being one such repeater inserted in each first selector trunk.

The first selectors are the first in the ¹⁰⁵ series of numerical switches which may comprise first selectors, second selectors, and connectors, which are used to complete con-

nections between calling and called lines. The reference characters F and H indicate, respectively, a second selector and connector. The second selector F is substantially 5 like the first selector E, and since these selectors and also the connectors are well known in the art, it has not been thought necessary to show the complete circuits. The substation A' (Fig. 2) is one of the 10 stations to which the connector H has access and may be similar to the substation A, although for convenience the measured service equipment has been omitted.

It is customary in automatic exchanges to 15 provide a special group of second selectors through the medium of which calling subscribers may connect with the various groups of trunk lines extending to the different operators and employees at the telephone 20 exchange, such for example as the information operators, the trouble operators, or the wire chief. These special second selectors are generally accessible from a certain level in the regular first selectors. In Fig. 25 a trunk line is shown which terminates in a set of bank contacts in the second level of the first selector E and which extends to a second selector F'. The second selector F' is one of a group of special second selectors 30 which have access to the groups of trunk lines above referred to. One of these trunk lines is shown in the drawing and terminates in the operator's equipment indicated by the reference character O, which comprises 35 a group of relays, an answering jack J, and a call signal lamp L.

In order to explain the operation of the 40 circuits it will first be assumed that the subscriber at substation A desires to call the operator having the equipment O, it being possible to accomplish this without depositing a coin as has been mentioned hereinbefore. When the receiver is removed at substation A a circuit is completed for 45 the line relay 23 of the line switch C in the usual manner, and upon energizing, the line relay closes at its armature 30 a circuit which extends from ground through the windings of the switching relay 24 and the 50 stepping magnet 25 to battery. At the same time relay 23 connects the test wiper 36 to the above circuit at a point midway between the switching relay and the said stepping magnet. The operation now depends upon 55 whether the trunk line with which the wipers of line switch C are associated is or is not busy. If the trunk line is busy the test contact with which the test wiper 36 is in engagement will be grounded, and as 60 a result the switching relay 24 will be short circuited and the stepping magnet 25 being supplied with a direct ground will operate as a buzzer to advance the switch wipers step by step in search of an idle trunk line. How- 65 ever, we may assume that when the call was

initiated the wipers of the line switch C were standing as shown in the drawing, in connection with the trunk line extending to the first selector E, and we may assume furthermore that this trunk line was idle. 70 Under these circumstances when the receiver is removed the energization of the line relay 23 is followed immediately by the energization of the switching relay 24, which is of sufficiently high resistance to prevent the 75 energization of the stepping magnet; and as a result of its energization the switching relay disconnects the line conductors 21 and 22 from the winding of the line relay and 80 from ground, respectively, and extends them by way of armatures 26 and 28 and their working contacts, wipers 35 and 37, bank contacts 38 and 40, armatures 63 and 65 and their resting contacts, armatures 76 and 79 and their resting contacts, and the upper 85 and lower windings of differential relay 54 to the windings of the line relay 57 and the impedance coil 62, respectively.

Following the extension of the line as 90 above described by the operation of the line switch C the line relay 57 of the repeater D is energized over the line circuit and at its armature 85 completes a circuit for the slow acting relay 58. Upon energizing, relay 58 completes a holding circuit extending 95 back to the line switch C over the following path: Ground at G², working contact of armature 88 and the said armature, winding of low resistance relay 55, conductor 98, test contact 39, test wiper 36, armature 27 100 and its working contact, winding of the switching relay 24, and the winding of the stepping magnet 25 to battery. It is understood that the above circuit is established before the line relay 23 has had time to de-energize. Relay 55 may be of about 50 ohms resistance and is low enough so that the multiples of the test contact 39 are made busy to other rotary line switches. The slow acting relay 58 also prepares a circuit 105 for relay 61 at its armature 87, closes the circuit of the lower winding of the electro polarized relay 59 at its armature 89, and at its armature 90 closes a contact in a special shunt circuit which will be described 110 later on.

When the line relay 57 of the repeater was 120 energized a bridge was closed across the trunk conductors 101 and 103 which may be traced as follows: Conductor 101, armature 92 and its resting contact, normally closed contact springs controlled by armature 76, upper winding of electro polarized relay 59, impedance coil 60, conductor 99, and armature 86 and its working contact to trunk conductor 103. Upon the closure of the bridge as above traced the line relay 104 of the first selector E is energized in the usual manner and closes the circuit of the slow acting release relay 105. Upon energizing 125 130

the relay 105 prepares the first selector for operation in its vertical movement, and also closes the usual holding circuit extending back to the preceding switch, the circuit being traceable as follows: Ground at G⁴, armature 151 and its working contact, resistance X, conductor 102, and the resting contact of armature 75 and the said armature to conductor 98 where it joins the previously described holding circuit extending back to the switching relay 24 of the line switch C. It will be seen that the holding circuit is supplied with ground from two points, both from G³ and G⁴, and it should be mentioned in this connection that the resistance X is approximately equal to the resistance of the relay 55 of the repeater D. It follows that the circuit through relay 55 will continue to supply approximately one half the current to the holding circuit after the line has been extended to the selector E and relay 55 will therefore remain energized.

Before proceeding further with the explanation, attention is called to a shunt circuit around the armature 86 and its working contact which, it may be mentioned, are the impulse springs of the repeater D which control the operation of the selector E and succeeding switches. This shunt circuit extends as follows: From armature 86 by way of a section of conductor 99, the resting contact of armature 81 and the said armature, resting contact of armature 84 and the said armature, and the working contact of armature 90 and the said armature to the working contact of the said armature 86. The contact at armature 90 is closed, but since relay 55 is energized armature 81 will be attracted and the shunt circuit will be open at that point, it being clear from this that the shunt circuit will not interfere with the action of the impulse springs represented by armature 86 and its working contact in repeating impulses.

The calling subscriber at substation A may now operate his calling device in accordance with the first of the two digits which it is necessary to call in order to obtain connection with the desired operator. By the operation of the calling device a series of interruptions is produced in the circuit of the line relay 57 in the well known manner, thereby causing a series of deenergizations of this line relay, which at each deenergization retracts its armature 86 to interrupt the circuit of the line relay 104 of the first selector E. At the first deenergization relay 57 sends an impulse of current through the winding of the slow acting relay 61 which is energized and which remains energized throughout the series of deenergizations. Relay 61, in operated position, closes at its armature 92 a direct bridge across the trunk conductors 101 and 103 which includes only the armature 86 of

relay 57 and its working contact, and also at its armature 93 short circuits the impedance coil 62. These circuit changes are brought about in order to reduce the resistance and impedance of the switch control circuits to a minimum during the transmission of impulses. Proceeding now to the selector E at each interruption of its circuit the line relay 104 deenergizes and transmits a current impulse through the vertical magnet 110 to battery, the vertical magnet being operated in the usual manner to raise the shaft of the switch step by step until the wipers stand opposite the bank level in which are terminated the trunk lines extending to the special second selectors, one of which is the selector F'. The slow acting relay 106 which is in series with the vertical magnet is energized at the first impulse and retains its armature attracted while the vertical magnet is being operated. At the first upward movement of the shaft a circuit is completed which extends from ground G⁴ by way of armature 151 and its working contact, armature 152 and its working contact, off-normal springs 113, and the winding of the stepping relay 107 to battery. The stepping relay 107 is accordingly energized and closes a locking circuit for itself at its armature 153. At the end of the vertical operation of the switch the slow acting relay 106 is deenergized, thereby closing a circuit for the rotary magnet 108, the circuit being readily traceable from armature 152 by way of its resting contact, armature 154 and its working contact, and the winding of the rotary magnet 108 to battery. Upon energizing, the rotary magnet 108 operates to advance the wipers 130-132, inclusive, into engagement with the first set of bank contacts in the level opposite which they were raised in the vertical movement of the switch, and also breaks the locking circuit of the stepping relay 107. Relay 107 therefore deenergizes and breaks the circuit of the rotary magnet 108, which accordingly retracts its armature and again closes the interrupter contact controlled thereby. The operation now depends upon whether the test wiper 131 is in engagement with a busy test contact or not. If the test contact with which the wiper 131 has made connection is busy it will be grounded, and the stepping relay 104 will again be energized over a circuit which includes the test wiper 131, armature 155 and its resting contact, the interrupter contact of the rotary magnet 108, and the off normal springs 113. The energization of the stepping relay 107 results in another closure of the circuit of the rotary magnet, which advances the wipers of the switch into engagement with the next set of bank contacts, and at the same time breaks the circuit of the stepping relay. This operation, by which the step- 130,

ping relay 107 and the rotary magnet 108 are alternately energized and deenergized takes place very rapidly and will continue until the test wiper 131 arrives at a non busy and ungrounded test contact. Assuming that the trunk line extending to the second selector F' is the first trunk line of the group, or at least first idle trunk line, when the test wiper 131 arrives at test contact 137 it will find no ground potential and the stepping relay 107 will not again be energized. Instead, the switching relay 109 which was connected in series with the stepping relay 107 upon the closure of off normal springs 113, and which until now has been short circuited, will energize with the result that the trunk conductors 101 and 103 are disconnected from the windings of the line relay 104 and are extended by way of wipers 130 and 132, bank contacts 136 and 138, trunk conductors 141 and 143 to the double wound line relay 200 of the second selector F'.

Line relay 200 is accordingly energized and closes a circuit for the slow acting release relay 201. Upon energizing relay 201 prepares the circuit of the vertical magnet at its lower armature in the usual manner and also completes the usual holding circuit which may be traced over the following path: Ground at G⁶, upper armature of relay 201 and its working contact, resistance X', conductor 142, test contact 137, test wiper 131, and armature 155 and its working contact to conductor 102, where it joins the holding circuit previously described. A branch of this circuit extends from conductor 102 by way of the winding of switching relay 109, the interrupter contact of the rotary magnet 108, off normal springs 113, and the winding of the stepping relay 107 to battery. Current flow over this branch serves to maintain the relay 109 energized thus retaining the selector E in operated position.

The calling subscriber may now operate his calling device in accordance with the second digit in the number, thereby producing a second series of interruptions in the line circuit which are repeated as before by the relay 57 of the repeater D to produce in this case a series of interruptions in the circuit of the line relay 200 of the second selector F'. The selector F' is exactly like selector E and its operation will not be described in detail. It will be sufficient to say that the shaft is raised step by step until the wipers 220-222, inclusive, stand opposite the level of bank contacts in which are terminated the trunk lines extending to the wanted operator's position, after which the wipers are automatically rotated in search of an idle trunk line. Assuming that the trunk line shown in the drawing is the first trunk line found to be idle the switch

wipers will finally be brought to rest in engagement with bank contacts 233-235, inclusive, whereupon the switching relay 203 will be energized. As a result the trunk conductors 141 and 143 are disconnected from the windings of the line relay 200 and are extended by way of wipers 220 and 222, and bank contacts 233 and 235 to the upper and lower windings of the double wound relay 250. Relay 250 is therefore energized and completes a circuit for the slow acting relay 251 which upon energizing in turn closes a circuit for the lamp signal L, and also completes the usual holding circuit which may be traced as follows: Ground at G⁶, working contact of armature 253 and the said armature, resistance X², bank contact 234, test wiper 221, and armature 204 and its working contact to the conductor 142 where it joins the holding circuit previously described. The switching relay 203 is maintained energized by current flow in a branch circuit similar to the one described in the case of relay 109 of selector E.

The required connection has now been established. The operator is provided with suitable cord circuits and other connective apparatus and when she perceives the lighted lamp L she will answer the call by inserting the answering plug of one of her cord circuits in the jack J. From this point on the operations may take any desired course, depending upon the wants of the subscriber, and will not be described. Disconnection is effected in the usual manner by the hanging up of the receiver at substation A. This operation causes relay 57 of the repeater to deenergize with the result that the slow acting relay 58 of the repeater is deenergized to disconnect ground G³ from the holding circuit. Relay 57 also opens the bridge across the trunk conductors 101 and 103 with the result that the relay 250 at the operator's position is deenergized, followed by the deenergization of the slow acting relay 251. This latter relay removes ground G⁶ from the holding circuit. The switching relays in the selector switches and in the line switch C now deenergize and the switches are thereby restored to normal position in the usual and well known manner. Operations in the repeater D which take place upon disconnection and which have to do with the collection and refunding of coins are of no importance in the case of a connection of the class just described, and will therefore be explained later on.

I will now describe the operation of the circuits in calling another subscriber's line, and it will first be assumed that a connection of this kind is attempted without depositing a coin in the coin collector. Assuming that the call is initiated by the subscriber at the substation A as before and that the desired line is the line of substation

A', Fig. 2, when the receiver is removed at substation A the operations by which the line of substation A is extended through the medium of the line switch C and the repeater D to the first selector E are identical with the operations described in the previous case and will not be repeated. The operation of the selector E by which the connection is further extended to a second selector likewise have already been described and in this case there is nothing new in this operation except that the wipers of the selector E are raised opposite a bank level in which are terminated trunk lines which extend to second selectors of the regular trunking system. The second selector F is a selector of this class and it will be assumed that the trunk line extending thereto is the first trunk line found to be idle and that the selector E established connection with the bank contacts 133-135, inclusive. The trunk conductors 101 and 103 will now be extended by the operation of the switching relay 109 by way of wipers 130 and 132, bank contacts 133 and 135 and the upper and lower armatures of switching relay 182 to the upper and lower windings of the line relay 180 of the selector F. Upon energizing, relay 180 closes the circuit of the slow acting release relay 181. Upon attracting its armature 170 relay 181 closes a holding circuit as follows: Ground at G', armature 170 and its working contact, conductor 171, test contact 134, test wiper 131, armature 155 and its working contact, conductor 102, and the resting contact of armature 75 and the said armature to conductor 98 where it joins the branch extending from ground G^a at the repeater D. It will be observed that the circuit above traced contains no resistance, such as the resistance X, and as a result relay 55 at the repeater D is practically short circuited. This relay therefore is deenergized and at its armature 81 closes the previously described shunt circuit around the armature 86 of relay 57 and its working contact, thereby rendering the said armature 86 ineffective to open the bridge across trunk conductors 101 and 103 when relay 57 is deenergized. When the calling subscriber now operates his dial in accordance with the next digit and produces another series of interruptions in the line circuit, the resulting deenergizations of the relay 57 will be of no effect and it will be apparent that the selector F can not be operated.

The difference in the two classes of switches will now be apparent. All those 60 selectors which are required to be used in extending a connection to an operator's position are provided with resistances similar to resistances X, and X'; while those switches which are used only in connections to local subscribers have the resistance omitted. It follows then that whenever it is attempted to use a switch of the latter class under the circumstances just described, where no coin has been deposited, the relay corresponding to relay 55 of the repeater in 70 use will be short circuited and deenergized to disable the operating circuit extending to the switch ahead, thus preventing further extension of the connection.

I will now describe the case where the 75 subscriber at substation A deposits a coin before calling, and in this connection will also explain briefly the process of collecting the coin at the termination of the conversation. It will be assumed that the subscriber 80 at substation A desires to establish connection with the subscriber at substation A'. The first operation is to deposit a coin of suitable denomination in the coin collecting mechanism provided for that purpose. This 85 mechanism is well understood and its operation need not be explained in detail. When the coin is deposited it descends past the trigger mechanism which is released by the coin with the result that the polarized magnet of the coin collecting mechanism is connected from the line conductor 22 to ground. The coin is held in suspense by a trap door, where it is adapted to be either refunded 90 or collected under control of the polarized magnet. The coin may be deposited either before or after the receiver is removed. In either case the latter operation brings about the operation of the rotary line switch C whereby the line is extended to an idle selector switch. Assuming that the selector E, Fig. 2, is the switch to which the connection is extended the operations are the same as have already been described and will not be repeated. With one exception, however. 105 When the line conductors 21 and 22 are connected by the operation of the line switch C with the windings of the relay 57 and impedance coil 62 of the repeater D the ground on the line unbalances the differential relay 110 54 which is included in the circuit and causes this relay to operate. It may be stated that the polarized magnet at the substation is of high resistance and does not materially interfere with the transmission 115 of operating impulses or with talking circuit, but is nevertheless sufficient to unbalance and cause relay 54 to energize as described. Upon attracting its armature 80 relay 54 closes a circuit for relay 56, which 120 relay establishes a locking circuit for itself at its armature 83. Relay 56 also grounds the holding circuit extending back to line switch C at its armature 82, and at its armature 84 opens the shunt circuit around the 125 impulsive springs represented by armature 86 and its working contact. This latter operation is the important thing to be considered at this time, for it obviously permits any of the switches in the exchange to be 130

operated no matter whether they are provided with resistances, such as the resistance X, or not. Relays 54 and 56 therefore constitute means responsive to the deposit of a 5 coin for rendering the repeater D operative to repeat impulses regardless of the type of switches which it is attempted to operate.

The calling subscriber may now operate his calling device in accordance with the 10 digits in the number of substation A'. The selector E will respond to the first digit in the same manner as has already been described, and the second selector F and connector H will be operated in the well 15 understood manner in response to the calling of the remaining digits to complete the connection to the desired line. Thereafter suitable ringing mechanism is operated automatically to signal the called subscriber. 20 When the receiver is removed at the called station talking current is supplied to the transmitter thereat through the windings of the double wound back bridge relay 300 of the connector which relay, upon energizing, 25 reverses the connections of the incoming line conductors in the usual manner. The direction of current flow in the bridge at the repeater D is therefore reversed causing the electro polarized relay 59 to operate 30 and close at its armature 91 the circuit of relay 53. Upon energizing, relay 53 establishes a locking circuit for itself at its armature 78, and at its armature 77 completes a circuit for the slow acting relay 52. The 35 latter relay, upon energizing, separates conductor 102 from the holding circuit extending back to line switch C at its armature 75, and at its other armatures effects certain circuit changes which will be considered later 40 on. In addition to the functions mentioned, relay 53 by means of its armatures 76 and 79 and contact springs controlled thereby disconnects the incoming line conductors from the windings of the line relay 57 and 45 the impedance coil 62 and connects them directly to the trunk conductors 101 and 103, respectively. Simultaneously with the operation above described the bridge across trunk conductors 101 and 103 is broken at 50 the normally closed contacts controlled by armature 76, and the line relay 301 of the connector switch is now maintained energized by current flow over a complete metallic circuit including the calling subscriber's 55 line. Relay 100, which was connected in bridge of trunk conductors 101 and 103 by the operation of relay 53, is of very high resistance (12,000 ohms or more) and being marginally adjusted, does not energize as 60 long as the line circuit is closed at the calling station.

When the conversation is finished both subscribers will hang up their receivers. When the receiver is replaced at substation A, the shunt around relay 100 is opened and

the said relay will accordingly energize by current flow from the line relay of the connector H. Upon attracting its armature, relay 100 opens the conductor 102 and thereby breaks the locking circuit of relay 53, 70 which deenergizes and disconnects relay 100 from in bridge of the trunk. Since the line is now open at substation A the line relay 57 of the repeater will not again be energized and the bridge including the upper 75 winding of the polarized winding relay 59 and the impedance coil 60 will not be re-established, from which it follows that the relays 301 and 302 of the connector H will deenergize. The latter relay removes ground from the holding circuit extending back in the direction of the calling line and also brings about the release of the connector switch. The removal of ground from the holding circuit permits relays 109 and 80 182 of selector switches E and F to deenergize, whereupon these switches are restored to normal by their release magnets in the usual manner.

At the repeater D, when relay 53 was de-energized the said relay, in addition to operations already described, closed a circuit at its armature 77 for the slow acting relay 50. Upon energizing, relay 50 breaks the locking circuit of relay 56 at the resting contact of its armature 64 and at the working contact of the same armature connects ground to conductor 98 in order to prevent the release of the line switch C. In addition, at armatures 63 and 65, relay 50 opens both sides of the line and at the working contact of the latter armature connects the battery B² to the line conductor 22 over the following path: Line conductor 22, armature 28 and its working contact, wiper 37, 100 bank contact 40, armature 65 and its working contact, winding of slow acting relay 51, armature 72 and its working contact, armature 71 and its resting contact, and resistance lamp to the battery B². Upon the 105 closure of the above circuit current flows from battery B² through the relay 51 and the polarized magnet at the substation A in series to ground, energizing both the relay 51 and the said magnet. Relay 51 closes at 110 its armature 66 a circuit for the relay 97, closes a locking circuit for relay 52 at its armature 67, and at armatures 68 and 69 connects both the incoming line conductors together and by way of a condenser to ground. Ordinarily the polarized magnet at substation A will respond at once to current from battery B² and will operate to collect the deposited coin and restore the entire coin collecting mechanism to normal condition, incidently, disconnecting itself 115 from the line conductor 22. However, it sometimes happens that the armature of the polarized magnet will stick and the relay 97 is provided to ensure the collection of 120 125 130

the coin in such a case. The interrupter I causes relay 97 to rapidly vibrate its armature and interrupt the circuit of battery B², or battery B' in case this battery is included 5 in the circuit, with the object of intermittently energizing the polarized magnet, this operation being generally effective to free the armature in case it should stick. When the circuit is finally broken permanently 10 by the operation of the polarized magnet and its disconnection from the line, slow acting relay 51 will deenergize and break the locking circuit of slow acting relay 52. The latter relay upon deenergizing breaks 15 the circuit of the slow acting relay 50, which upon deenergizing removes ground from conductor 98, thus permitting the switching relay 24 of line switch C to deenergize. All the apparatus will now be in normal 20 condition and ready for another call.

In case the called subscriber did not answer it will be necessary to refund the deposited coin rather than collect it, when the calling subscriber replaces his receiver, and 25 this refunding operation will now be explained briefly. Since the called subscriber did not answer neither the polarized relay 59 or relays 52 and 53 of the repeater D will be energized, but the line relay 57 and the 30 slow acting relay 58 will be energized. Now when the calling subscriber hangs up his receiver relay 57 deenergizes and closes a circuit for the slow acting relay 61 and at the same time breaks the circuit of the slow 35 acting relay 58. When the latter relay deenergizes a circuit is completed at its armature 89 which extends by way of armature 94 of relay 61 and the winding of slow acting relay 50 to battery. Upon energizing, relay 50 operates as before described, except that in the present case, since relay 52 is deenergized, battery B' is connected to line conductor 22 instead of battery B². Current flow from battery B' now operates 40 relay 51 and the polarized magnet at the substation in series, the latter being now actuated to refund the deposited coin instead of collect it. Upon energizing, relay 51 completes a locking circuit for relay 50 at its armature 67, and produces other circuit changes which have already been described. 45 When the circuit is broken by the disconnection of the polarized magnet at the substation, relay 51 deenergizes followed by the deenergization of relay 50, and the release of the line switch C, whereupon all the apparatus will have been restored to normal.

While I have described a certain specific embodiment of my invention I recognize 50 that the same may be modified to adapt it for use in connection with other types of automatic switching mechanism and with other types of measured service equipment. I do not wish therefore to be limited to the 55 precise form herein disclosed, but desire to

secure and have protected by Letters Patent all forms of my invention which may hereinafter be devised, limited only by the scope of the appended claims.

What I claim as my invention is:

1. In a telephone system, subscribers' lines extending to a central exchange, measured service equipment at the station on each line, an impulse sender at the station on each line independent of the associated measured 70 service equipment, automatic selector switches of two classes at the exchange, said switches controlled by said senders, and means at the exchange for rendering the switches of one class operable only under 75 control of said equipment, and the switches of the other class operable independent of said equipment.

2. In a telephone system, a subscribers' line extending to a central exchange, coin 80 collecting mechanism at the station on said line, automatic selector switches at the exchange normally uncontrollable from said station, means at the exchange effective only after a coin has been deposited in said mechanism for permitting said selectors to be controlled from said station, and other selector switches at the exchange controllable from 85 said station without depositing a coin.

3. In a telephone system, subscribers' 90 lines, automatic switches controllable over calling subscribers' lines for connecting with called lines, discriminating equipment at the exchange, measured service apparatus at the station on each line requiring the subscriber 100 to charge himself with a call to effect the operation of said equipment before a connection can be set up by means of said switches, an operator's position, and other automatic switches controllable over calling 105 lines for connecting with said operator's position without charge.

4. In a telephone system, a calling and a called subscriber's lines, an automatic switch controllable from the station on the calling 110 line to complete a connection with said called line, paystation equipment at the calling station, means at the exchange requiring a coin to be deposited in said paystation before said switch can be operated, an operator's position, another automatic switch, 115 and means individual to said second switch rendering the same controllable from said station to complete a connection to said operator's position without depositing a 120 coin.

5. In a telephone system, automatic substations, paystation equipment at each of 125 said substations, an operator's position, automatic switches of two classes for completing connections to subscribers' lines and to said operator's position, respectively, circuit arrangements at the exchange common to all said switches and such that a coin must be deposited in the paystation at a calling sta- 130

tion for each connection established by means of switches of the first class, and means causing the switches of the second class to be unaffected by said circuit arrangements, thereby permitting connections to be established by means of switches of the second class free of charge.

6. In a measured service telephone system, trunk lines at the exchange each terminating in an automatic switch, a release trunk conductor for each trunk line, means requiring calling subscribers to pay before operating certain of said switches, and resistances included in the release trunk conductors associated with certain other of said switches, whereby such switches may be operated free.

7. In a measured service telephone system, a repeater and associated first selector switch at the exchange, trunk lines accessible to said switch each terminating in a second selector switch, a release trunk conductor in each trunk line, resistances in the release trunk conductors extending to certain of said second selectors only, and means in said repeater for preventing a calling subscriber from operating those selectors whose associated release trunk conductors have no resistances unless the connection has been paid for in advance.

8. In a telephone system, a subscriber's station, a paystation device at said station, automatic switches at the exchange, a repeater interposed between said line and switches, a control circuit extending from said repeater for operating said switches, and means in certain of said switches for rendering said control circuit inoperative unless a coin has been deposited in said device.

9. In a telephone system, a subscriber's station, a paystation device at said station, automatic switches at the exchange, a repeater interposed between said line and switches, a control circuit extending from said repeater for operating said switches, an operator's position accessible to certain of said switches, a called subscriber's line accessible to certain other of said switches, and means in the said latter switches only for rendering said control circuit inoperative unless a coin has been deposited in said device.

10. In a telephone system, a subscriber's line extending to a central exchange, coin collecting mechanism at the station on said line, serially related automatic switches at the exchange, a repeater interposed between the said line and switches, a normally inoperative control circuit extending from the repeater to the first one of said switches, and means responsive to the deposit of a coin in said mechanism for rendering said circuit operative.

11. In a telephone system, a subscriber's

line extending to a central exchange, coin collecting mechanism at the station on said line, serially related automatic switches at the exchange, a repeater interposed between the said line and switches, a control circuit extending from the repeater to one of said switches and including interrupter contacts for controlling the same to operate said switch, a shunt path around said contacts, and means responsive to the deposit of a coin in said mechanism for opening said shunt.

12. In a telephone system, a subscriber's line extending to a central exchange, coin collecting mechanism at the station on said line, serially related automatic switches at the exchange, a repeater interposed between the said line and switches, a normally inoperative control circuit extending from the repeater to the first one of said switches, means in said repeater for rendering said circuit operative when the line is calling, and means in another switch in the series for rendering said circuit again inoperative.

13. In a telephone system, a subscriber's line extending to a central exchange, coin collecting mechanism at the station on said line, serially related automatic switches at the exchange, a repeater interposed between the said line and switches, a control circuit extending from the repeater to one of said switches and including interrupter contacts for controlling the same to operate said switch, a shunt path around said contacts, means in said repeater for opening said shunt when the said line is calling, and means in another switch in the series for again closing said shunt.

14. In a telephone system, a subscriber's line extending to a central exchange, coin collecting mechanism at the station on said line, a group of selector switches at the exchange always operable from said station free of charge, other selector switches directly accessible to the selectors of said group and also always operable from said station free of charge, still other selectors directly accessible to the selectors of said group, and means at the exchange effective only after suitable coins have been deposited in said collecting mechanism for permitting selectors of said last group to be operated.

15. In a telephone system, a subscriber's line extending to a central exchange, coin collect apparatus at the station on said line, automatic switches of two classes at the exchange, impulse sending mechanism at the station on said line operable independent of said coin collect apparatus to transmit impulses to the exchange, and means at the exchange for rendering the impulses transmitted ineffective to control the switches of a certain one of said classes unless a coin has been deposited in said coin collect apparatus, while the switches in the other class

are always responsive whether a coin is deposited or not.

16. In a telephone system, paystation lines extending to a central exchange, automatic switches of two classes, means including impulse senders at the stations on said lines for controlling series of said automatic switches to extend connections to called lines, and means at the exchange for preventing the automatic switches of only one class from being operated under control of said senders unless coins are deposited in the paystations on the calling lines.

17. In an automatic telephone system, the combination of a calling and called telephone lines, automatic switches for interconnecting said lines, a coin collector at the calling station having a magnet, sources of uninterrupted current at the central office of different character for operating said magnet either to refund or collect a deposited coin, means controlled by the called party for selecting the source to be connected to the calling line to selectively operate said magnet, means automatically actuated by the replacement of the receiver by the calling party for momentarily applying current from the selected source to the calling line, and means for thereafter intermittently applying said source to said line until the coin is refunded or collected.

18. In an automatic telephone system, the combination of calling and called telephone lines, automatic switches for interconnecting said lines, a coin collector at the calling station having a magnet, sources of current of different character for operating said magnet, either to refund or collect a deposited coin, means controlled by the called party for selecting the source to be connected to the calling line to selectively operate said magnet, means automatically actuated by the replacement of the receiver by the calling party for momentarily applying the selected current to the calling line, and means at the exchange responsive to the momentary application of current to the calling line for causing said current to be thereafter intermittently applied until the coin has been collected or refunded.

19. In an automatic telephone system, calling lines equipped with paystation mechanism, called lines of two classes, automatic switches for partially setting up a connection to either class of called lines, other switches accessible to said first switches some of which other switches have access to one class of called lines while others have access to called lines of the other class, and means provided only in switches of one class making it necessary for a calling subscriber to deposit a coin in the paystation mechanism before a talking connection can be completed.

20. In a telephone system, calling lines

equipped with paystation mechanism, called lines of two classes, means including an automatic switch individual to one class of called lines for completing connections without requiring a coin to be deposited in said paystation mechanism, and means including an automatic switch individual to the other class of lines for requiring a coin to be deposited in the paystation mechanism before a talking connection can be completed.

21. In a telephone system, calling lines equipped with paystation mechanism, called lines of two classes, groups of automatic switches each group having access to called lines of a different class, trunk lines accessible to the calling lines terminating in automatic switches having access to either class of said first mentioned automatic switches, and means in said trunk lines controlled by means in the automatic switches of only one class making it necessary for a coin to be deposited in said paystation mechanism before a talking connection can be completed.

22. In a telephone system, calling lines equipped with coin collect mechanism, called lines of two classes, groups of automatic switches, each group having access to a particular class of called lines, trunk lines accessible to said calling line terminating in automatic switches having access to said first switches, means in said trunk lines for preventing the establishment of connections to one class of called lines, rendered ineffective by the deposit of a coin in said mechanism, and means in the automatic switches having access to the other class of called lines for also rendering said means ineffective.

23. In a telephone system, calling lines provided with paystation mechanism, called lines of two classes, means at the exchange including automatic switches controlled over any calling line for setting up talking connections to called lines of either class, means also at the exchange rendering the establishment of talking connections to lines of one class possible without requiring the deposit of a coin in the paystation mechanism, and means rendering the establishment of talking connections to subscribers of the other class impossible until a coin has been deposited.

24. In a telephone system, calling lines equipped with measured service equipment at the station on each line, an impulse sender at the station on each line independent of the associated measured service equipment, called lines of two classes, automatic switches at the exchange, means at the exchange requiring a coin to be deposited in said paystation mechanism before a connection can be completed to lines of one class, and means independent of said pay-

station mechanism for rendering said means at the exchange ineffective when lines of the other class are called.

25. In a telephone exchange system, calling lines provided with paystation mechanism, called lines of different classes, means for extending connections from said calling lines to called lines of all classes, and circuit arrangements at the exchange requiring 10 the deposit of a coin in said paystation mechanism before a talking connection can be completed to a line of a particular class.

26. In a telephone exchange system, calling lines, paystations for said lines, called 15 lines of two classes, means for extending connections to lines of either class, and circuit arrangements at the exchange requiring the deposit of a coin in said paystation mechanism before a talking connection can 20 be completed to lines of one class.

27. In a repeater for an automatic paystation telephone system, a trunk line extending through said repeater and comprising 25 two sections, a line relay bridged across the incoming section, contacts on said line relay for closing a bridge across the outgoing section and for interrupting the same subsequently responsive to interruptions in the incoming section, a shunt around said 30 contacts, a differential relay in series with said line relay, and means controlled by said differential relay for opening said shunt.

28. In a repeater for an automatic paystation telephone system, a trunk line extending through said repeater and comprising

ing two sections, a line relay bridged across the incoming section, contacts on said line relay for closing a bridge across the outgoing section and for interrupting the same 40 subsequently responsive to interruptions in the incoming section, a shunt around said contacts, a release trunk conductor included in said trunk line, a relay for opening said shunt, and a circuit over which ground is connected to said conductor through the 45 winding of said last mentioned relay.

29. In a repeater for an automatic paystation telephone system, a trunk line extending through said repeater and comprising 50 two sections, a line relay bridged across the incoming section, contacts on said line relay for closing a bridge across the outgoing section and for interrupting the same subsequently responsive to interruptions in the incoming section, a shunt circuit around 55 said contacts, two sets of contacts included in said shunt circuit in series, a differential relay in series with said line relay, means controlled by said differential relay for opening one of said sets of shunt circuit 60 contacts, a release trunk conductor included in said trunk line, a relay controlling the second of said sets of shunt circuit contacts, and a circuit over which ground is connected to said release trunk conductor 65 through the winding of said relay.

Signed by me at Chicago, Cook County, Illinois, this 14th day of January, 1920.

JOHN WICKS.
